CLAIM

The ornamental design for an anti-glare monitor filter holder, as shown and described.

DESCRIPTION

FIG. 1 is a perspective view of an anti-glare monitor filter holder showing our new design, the broken line drawing of a computer terminal is for illustrative purposes only and forms no part of the claimed design;

FIG. 2 is a top perspective view thereof;

FIG. 3 is a top plan view thereof;

FIG. 4 is a front elevational view thereof;

FIG. 5 is a side elevational view thereof, the opposite side being a mirror image;

FIG. 6 is a rear elevational view thereof; and,

FIG. 7 is a bottom plan view thereof.
